[57] CLAIM

The ornamental design for a cover for rear of motorcycle, as shown and described.

DESCRIPTION

FIG. 1 is a side perspective view of a cover for the rear of a motorcycle showing my new design;

FIG. 2 is a top plan view thereof;

FIG. 3 is a right side elevation view thereof;

FIG. 4 is a left side elevation view thereof;

FIG. 5 is a bottom plan view thereof;

FIG. 6 is a front elevation view thereof; and,

FIG. 7 is a rear elevation view thereof.

The portions of the motorcycle shown in broken lines in FIG. 1 are for illustrative purposes only and form no part of the claimed design.
